JAMES E. BANCROFT, OF DETROIT, MICHIGAN, ASSIGNOR TO DOOR-MOTIVE CORPORATION, OF WORCESTER, MASSACHUSETTS, A CORPORATION OF MASSACHUSETTS

ELECTRIC SWITCH

Application filed October 12, 1928. Serial No. 312,095.

This invention relates to control devices, and more particularly to electro-magnetically operated electric switches.

Switches of this type are frequently arranged in pairs for various purposes, such as the operation of a reversing electric motor, one switch being used to operate the motor in a forward direction and the other in a reverse direction. Mechanism is usually provided to interlock the switches and thereby eliminate any possibility of one switch being closed before the other is opened. The operation of the switches is ordinarily controlled by means of push buttons, and it has heretofore been customary to utilize three push buttons for each pair of switches, one to start the motor in a forward direction, one to stop the motor, and one to start it in a reverse direction.

It is one object of my invention to provide a construction whereby two push buttons will give complete control over a pair of interlocked switches, permitting either switch to be opened or closed at will.

It is a further object of my invention to provide a simply constructed and inexpensive interlocking mechanism for a pair of electro-magnetically operated switches.

It is a further object to provide an interlocking mechanism which will form part of the holding circuit of a closed switch and maintain the switch in a closed position after the release of the corresponding push button.

It is a further object to provide an interlocking mechanism which will automatically open a closed switch whenever an attempt is made to close the other switch.

With these and other objects in view, as will be apparent to those skilled in the art, my invention resides in the combination of parts set forth in the specification and covered by the claims appended hereto.

In accordance with my invention, I provide a pair of electric switches, each having a solenoid, or electro-magnet arranged for its actuation. I provide an interlocking mechanism which is so constructed and arranged as to prevent either switch from being closed except when the other is open. The inter-

locking mechanism preferably completes a circuit when a switch is closed so as to maintain the current flow in the corresponding solenoid. The parts are preferably so constructed that an attempt to close an open switch when the other switch is closed will cause the latter switch to open.

Referring to the drawings illustrating one embodiment of my invention and in which like reference numerals indicate like parts;

Fig. 1 is a side elevation of the device, with one switch in the closed position;

Fig. 2 is a cross section on the line 2—2 of Fig. 1;

Fig. 3 is a cross section on the line 3—3 of Fig. 1; certain parts being omitted for clearness of illustration;

Fig. 4 is a view similar to Fig. 3, except that both switches are open;

Fig. 5 is a view similar to Fig. 3, showing the position of the parts immediately after an attempt is made to close the open switch;

Fig. 6 is a wiring diagram of the holding circuits; and

Fig. 7 is a wiring diagram of the main switch circuits.

The embodiment illustrated comprises a vertical rectangular supporting panel 10, preferably constructed of insulating material. On opposite sides of the panel and near the lower portion thereof, I mount a pair of brackets 11 and 12 arranged to support the switch members 14 and 15, which are preferably pivotally attached to the brackets by means of horizontal pins 17 and 18. These parts are so shaped and arranged that the upper portions of the switch members tend to fall outwardly away from the panel under the influence of gravity, and this outward pivotal movement is limited by downwardly extending projections 20 and 21 on the switch members, which strike against lugs 23 and 24 formed on the brackets. With this construction each switch is biased to the open position.

The switch members 14 and 15 are arranged to carry sets of contacts 26 and 27 respectively. Though I have shown three of these contacts in each group, the particular number is immaterial so far as the present invention

is concerned, but depends entirely upon the use to which the device is to be put. In order to provide a suitable support for the contacts, each switch member carries near its upper extremity a horizontal rectangular bar 29 of insulating material, on which are mounted downwardly extending arms 30. The contacts 26 and 27 are pivoted at their lower extremities to the lower portions of the arms 30 and are normally held against the upper ends of the arms by small compression springs 32 which bear against the enlarged heads of rivets 33 attached to the arms 30. The pivotal connection between the contacts 26 and 27 and the arms 30 may be formed in any suitable manner. As shown, the contacts have reduced ends projecting into openings 31 in the arms 30.

Cooperating with the contacts 26 and 27 is a set of three contacts 35 which preferably extend entirely through the upper portion of the panel and are provided with enlarged heads 36 at their ends. These parts are so shaped and located that when the switch members are swung inwardly the contacts will touch, and the springs 32 will insure an even bearing pressure.

As an illustration of one use to which the device may be put, I have shown the main switches connected in Fig. 7 to operate a motor 38 of the three phase induction type. The three phase power supply 39 is connected to the stationary contacts 35, and the motor is connected to the movable contacts 26 and 27, two of the connections being crossed as shown, in a manner well known in this art, in order to provide for running the motor in either direction.

In order to close the main switches when desired, I provide each switch member with an armature 41 of magnetic material, these armatures being mounted on the inward side of the switch member toward the central panel. On opposite sides of the panel I mount a pair of solenoids or electro-magnets 43 and 44, which are so located that when energized they will attract the corresponding armature and thus pull the corresponding switch member inwardly. The solenoid connections may be wired as shown diagrammatically in Fig. 6. Solenoid 43 is connected by a wire 46 to one side of a series of push buttons or control switches 47, and by a wire 49 to one side of a power supply 50, which may consist of a battery or generator, or any other suitable source of electric energy. Solenoid 44 is connected to the wire 49 and by means of a wire 51 to one side of another series of push buttons 52. Both sets of push buttons are connected by a wire 53 to the other side of the power supply 50. There may be any number of push buttons, located at places convenient for the operator.

It will be noted that with the device as so far described, if one push button 52 is actu-

ated and one push button 47 is then actuated before the other is released, both solenoids will be energized at the same time, which will cause the closing of both main switches and a short circuit of the main power supply 39. Moreover, in order to maintain energization of either solenoid and thus hold the switch closed, it is necessary to hold the proper push button closed. This is, of course, inconvenient.

In order to overcome these difficulties, I provide an interlocking device which in the present embodiment comprises an interlocking member or bar 60. This bar extends through an opening in the panel 10 in a direction substantially perpendicular thereto, and is mounted for pivotal movement on a horizontal pin 61 attached to a bracket 63, which is fastened to the panel. The bar 60 is yieldingly held in a horizontal position symmetrical with respect to both switch members by a small coiled spring 64 surrounding the pin 61 and arranged with one end fastened to the bracket 63 and the other end attached to the interlocking bar.

For cooperation with the interlocking bar I provide a pair of interlocking fingers 66 and 67, one on each of the insulating bars 29. Each finger is made of conducting material, and is preferably bent inwardly and downwardly at its upper extremity 68 as shown, in order to more effectively co-act with the bar 60. For this same purpose, the bar 60 is preferably formed with bluntly pointed wedge shaped ends so arranged as form cam surfaces adapted to contact on their tapered sides with the tops of the downwardly bent ends 68 of the bar 60.

As shown in Fig. 6, the bar 60 is connected by a wire 69 to wire 53; finger 66 is connected to wire 46; and finger 67 is connected to wire 51. The parts are so arranged that when either main switch is closed, the corresponding interlocking finger will strike against the interlocking bar 60, thus closing an independent circuit across the push button used to close the main switch. This push button can then be released without de-energizing the solenoid and opening the switch.

Moreover, as one switch is moved to its closed position, the interlocking finger tips up the interlocking bar owing to the wedge shapes of the contacting parts, thus lowering the other end of the bar into the path of the other finger, and prevents closing of the other main switch. Suitable insulation is provided to prevent electrical contact of the interlocking bar 60 with the fingers 66 or 67 of the open switch, when the bar is thus tipped. As illustrated, this insulation may be accomplished by mounting a small block or cam member 70 on each finger and insulating it therefrom. Each block 70 has its upper side shaped to lie in the plane of the beveled top edge of the part 68 so that the lower

beveled edge of the bar 60 may ride over the block 70 when moving to the position shown at the right hand end of Fig. 3. Each block 70 has a cam surface 72 so shaped that if an attempt is made to close the other main

5 switch, the cam surface 72 will strike the upper side 73 of the beveled end of the bar 60 (Fig. 3) and force it down still more, as shown in Fig. 5, thereby breaking the connection between the bar and the other finger and de-energizing the other solenoid. The interlocking bar is prevented from tipping too far by providing the block 70 with a notch 74, as shown in Figs. 3 and 5, which fits the end of the bar 60 and prevents further downward movement of that end.

10 The operation of my invention will now be apparent from the above disclosure. With the parts in the position shown in Fig. 4, both main switches are open, and the motor 38 is at rest. If now one of the push buttons 52 is closed momentarily, a circuit is established through wire 53, wire 51, solenoid 44, and wire 49. Solenoid 44 is therefore energized, and will attract armature 41 on switch member 15. The switch arm will swing upwardly and inwardly about pin 18, and contacts 27 will strike against contacts 35, thus connecting motor 38 to power supply 39 and starting the motor in a forward direction.

15 As the main switch closes, finger 67 strikes the underside of the bar 60, thus tipping it upwardly against the action of spring 64, as shown in Fig. 3, and short-circuiting push button 52 through wire 69. This, therefore, maintains energization of solenoid 44, and push button 52 can be released without causing the main switch to open.

20 In case it is now desired to stop the motor, it is merely necessary to press one of the push buttons 47 momentarily. This closes a circuit through wire 53, wire 46, solenoid 43, and wire 49, energizing solenoid 43 and attracting armature 41 on switch member 14. This switch member swings in until cam block 70 strikes the top 73 of the bar 60 and swings that end downwardly, as shown in Fig. 5, the movement being insufficient to effect closure between contacts 26 and 35, but sufficient to 25 lift the opposite end of bar 60 and break its contact with finger 67. This de-energizes solenoid 44, and switch member 15 falls out, stopping the motor. Since block 70 is insulated, its contact with the interlocking bar 30 does not maintain energization of solenoid 43, and switch member 14 will drop back upon release of push button 47, whereupon the parts resume their original positions shown in Fig. 4. To operate the motor in the opposite direction it is now merely necessary to press one of the buttons 47 again. Since the two sides of the device are symmetrical, the resulting effects will be clear from the above description.

35 After the motor has been started running

in a given direction by one of the push buttons, it may be stopped by pressing the opposite push button, and it may be started in the reverse direction by pressing this same button a second time. The interlocking mechanism is simple and inexpensive, and effectively prevents closure of one main switch before opening the other. The omission of the third push button heretofore used to open the switch simplifies the wiring and installation. It will be apparent from the above disclosure that the solenoids may be arranged to effect opening of the switches as well as for closing them, and the claims presented herewith are to be given such an interpretation as will cover either arrangement.

Having thus described my invention, what I claim as new and desire to secure by Letters Patent is:—

1. A control device comprising an electric switch, a solenoid arranged to throw the switch in one direction when energized, a second electric switch, a second solenoid arranged to throw the second switch in one direction when energized, an interlocking device including a member normally in an open circuit with said solenoids which is arranged to permit the operation of either switch alone and prevent the simultaneous operation of both switches, and means forming an electrical connection, when either switch is initially thrown by its solenoid, between said member and the solenoid corresponding to the switch being thrown to maintain energization of said solenoid and hold the switch in the new position.

2. A control device comprising an electric switch, a solenoid arranged to actuate the switch when energized, a second electric switch, a second solenoid arranged to actuate the second switch when energized, an interlocking member arranged to prevent the simultaneous actuation of both switches, and means connecting a part of the interlocking member in an electrical circuit with one solenoid after actuation of the corresponding switch to cause this solenoid to remain energized.

3. A control device comprising an electric switch biased to an open position, a solenoid arranged to close the switch when energized, a second electric switch biased to an open position, a second solenoid arranged to close the second switch when energized, a mechanism arranged to prevent the closing of either switch when the other switch is closed, and means forming an electrical connection, when either of said switches is closed by the completion of a circuit through the corresponding solenoid and its resulting energization, which completes an independent circuit through the corresponding solenoid and thereby maintains energization of the solenoid after the opening of the first circuit.

4. A control device comprising an electric

switch biased to a given position, a solenoid arranged to move the switch when energized, a second electric switch biased to a given position, a second solenoid arranged to move the 5 second switch when energized, and means effective, after one solenoid has been energized, to de-energize this solenoid upon energization of the other solenoid.

5. A control device comprising an electric 10 switch, a solenoid arranged to actuate the switch when energized, a second electric switch, a second solenoid arranged to actuate the second switch when energized, means forming an electrical connection, when either 15 of said switches is actuated by the completion of a circuit through the corresponding solenoid and its resulting energization, which completes an independent circuit through the corresponding solenoid and thereby maintains energization of the solenoid after the 20 opening of the first circuit, and means effective to open this independent circuit and de-energize the solenoid upon energization of the other solenoid.

25 6. A control device comprising two switches having members biased to open position, a solenoid arranged to close each switch independently of the other when energized by the completion of a circuit therethrough, 30 means effective, when a switch is closed, to maintain energization of the corresponding solenoid by the completion of an independent circuit therethrough, thereby holding the switch closed after the first circuit has been 35 opened, and means to open the independent circuit and thereby de-energize the solenoid corresponding to the closed switch when the other solenoid is energized, thus causing the closed switch to open.

40 7. A control device comprising an electric switch, a solenoid arranged to close the switch when energized, a second electric switch, a second solenoid arranged to close the second switch when energized, an interlocking member 45 arranged to prevent the simultaneous closing of both switches, means to connect the interlocking member in series with a solenoid when the corresponding switch is closed by the completion of a circuit through 50 the solenoid, and thereby complete an independent circuit which serves to maintain energization of the solenoid after opening of the first circuit, and means to break the connection with the interlocking member upon 55 energization of the other solenoid.

8. A control device comprising a pair of electric switch members biased to a given position, a solenoid for each switch member arranged to move the switch member when 60 energized, a contact member movable with each switch, and a movable interlocking mechanism arranged to make electrical contact with either contact member when the corresponding switch is operated and complete a circuit through the solenoid and

thereby maintain it energized, said mechanism and contact member being so constructed that when one switch member is moved the mechanism is moved to a position which prevents operation of the other switch. 70

9. A control device comprising a pair of electric switches having movable members biased to an open position, a solenoid for each switch arranged to move its switch member to a closed position when energized, a movable interlocking bar, a contact member movable with each switch member arranged to contact with said bar, when one of the switches is closed, and complete an electric circuit through the corresponding solenoid and to simultaneously move the bar to a second position, and insulation so located and arranged as to prevent electric contact of the bar in such second position with the other contact member when an attempt is made to close the other switch. 80

10. A control device comprising a pair of electric switches having movable members biased to an open position, a solenoid for each switch arranged to move its switch member to a closed position when energized, a pivotally mounted interlocking bar normally located in an inoperative position, a finger movable with each switch member to engage said bar and move it to a second position, said bar and the finger engaged thereby serving to close a circuit to the corresponding solenoid and hold the switch closed, the other finger being arranged to move the bar to a third position and out of electrical contact with the engaged finger when an attempt is made to close the other main switch, and insulation between said other finger and the bar to prevent electrical contact therebetween while the bar is being so moved from said second 105 position.

11. A control device comprising two opposed pivotally mounted switch members biased to an open position, solenoids connected to close the switches, fingers movable with the switch members, and an interlocking bar pivotally mounted so that one end may make electrical contact with one of said fingers when the corresponding switch is closed and its other end will move into the path of the other finger and prevent both switches from being closed simultaneously, said finger and bar when in contact forming an electric circuit through the corresponding solenoid to maintain the same energized. 110

12. A control device comprising two main switches having opposed pivotally mounted switch members biased to an open position, two solenoids connected to close said switch members, fingers mounted to move with the switch members, a bar pivotally mounted between the switch members and arranged so that its ends may electrically contact with either one of said fingers and make a circuit through the solenoid which actuates the cor- 120

responding switch, said bar having cam surfaces at its opposite ends engageable by said fingers which are so shaped that when one switch is closed the corresponding finger moves the bar to a position which interferes with free movement of the other finger and its switch, and insulation arranged to prevent electrical contact between the opposite finger and the bar.

13. A control device comprising a pair of electric switch members pivotally mounted on a panel and biased to an open position, a solenoid for each switch member arranged when energized to close the switch corresponding thereto, an interlocking bar pivotally mounted on the panel between the switch members, means to hold the bar yieldingly in a position symmetrical with respect to both switch members, a contact on each switch member arranged to strike the bar when the switch is closed and deflect it from its normal position while at the same time completing a circuit through the solenoid corresponding to the closed switch, and an insulated member on each switch member which is so shaped as to strike the interlocking bar if an attempt is made to close a switch while the other is closed and deflect the bar even more from its normal position, thereby breaking the circuit through the solenoid corresponding to the closed switch and causing this switch to open.

14. A control device comprising two switches having opposed pivotally mounted switch members biased to an open position, two solenoids connected to close said switch members, fingers mounted to move with the switch members, a bar pivotally mounted so that its ends may contact successively with the fingers, cam surfaces on the top and the bottom of each end of the bar, said parts being so arranged that closing a switch causes a finger to make electrical contact with the under cam surface on one end of the bar and rock the other end into the path of movement of the other finger, insulation so located as to prevent electrical contact between said other end and the other finger, electrical connections between the bar and the contacting finger through the solenoid of the switch which has been closed, and a cam surface on each finger engageable with the top cam surface of the bar and arranged to move the bar, if an attempt is made to close a switch while the other is closed, and thereby break the electrical contact between the bar and the first engaged finger and so release the closed switch member.

Signed at Detroit, Michigan, this 8th day
of October, 1928.

JAMES E. BANCROFT.
